UNITED STATES PATENT OFFICE.

SIDNEY GEORGE BROWN, OF LONDON, ENGLAND.

TELEPHONY.

1,133,923.

Specification of Letters Patent. Patented Mar. 30, 1915.

Application filed July 6, 1914. Serial No. 849,261.

To all whom it may concern:

Be it known that I, SIDNEY GEORGE BROWN, a subject of the King of Great Britain, residing at 4 Great Winchester street, in the city and county of London, England, have invented certain new and useful Improvements in or Relating to Telephony, of which the following is a specification.

This invention relates to telephony and has reference to telephone relay systems of the kind in which the two stations between which communication is established are connected by way of relay apparatus so arranged that when voice currents originating in a transmitter at one station are sent along the line to the relay apparatus the distant receiving station is rendered incapable of operating the relay apparatus but is connected with the source of magnified voice currents produced in the said relay apparatus. In the specification of my prior British Patent No. 9179 of 1912 I have described several arrangements for operating in this manner.

The chief objects of the present invention are to improve the system of working in certain respects so as to allow a speaking operator to remain permanently in circuit with a distant station until the operator at that station speaks, to enable the vibration or similar device that responds to voice currents and operates in conjunction with the relay apparatus to be less delicate than has hitherto been necessary, and to guard against disturbances of the vibration device from external influences on the line.

According to the present invention relay apparatus at the relay station is associated with a change-over switch adapted to be moved automatically into one or other position immediately voice currents commence to flow from one or other of the terminal stations, thereby placing the particular station from which the voice currents originate in permanent connection with the energizing portion of the relay apparatus, and placing the reinforcing portion of this apparatus in permanent connection with the other station, until varying currents are produced by speaking at the latter station, whereupon the electrical conditions are immediately reversed.

The use of a double-pole change-over switch enables the relay apparatus to consist of a single telephone relay, thus affording simplification and economy of working, and

reducing attention on the part of the operator to a minimum.

In order that the invention may be clearly understood and readily carried into effect, I will now describe the same more fully with reference to the accompanying drawings, in which:

Figure 1 represents diagrammatically one arrangement of apparatus constituting a telephone relay system adapted to operate in accordance with the invention. Figs. 1^a and 1^b are fragmentary diagrams illustrating modifications. Fig. 2 is a modification of the system shown in Fig. 1, and Figs. 3 and 4 are two further modifications.

I will first describe the relay system as illustrated in Fig. 1. A and B represent the ends of two subscribers' lines inductively coupled to the two ends of the line sections proper L^a L^b between which is inserted the relay apparatus. The relay apparatus comprises the relay proper C, with which is associated the double-pole throw-over switch D, the latter being represented by the two arms D¹ D² and their associated electro-magnetic actuating means d¹ d¹₁, d² d²₁. The relay C may be a telephone relay of any ordinary construction such as an electromagnet operating a microphone as shown, its energizing portion, represented by the terminals C¹, forming part of one or other of two circuits including two contacts c¹, c² of the double pole switch D, and its reinforcing portion, represented by the terminals C², forming part of two circuits including the other two contacts namely c¹, c², of the said switch. The circuit connections and the construction of the double pole switch D are such that when one of the relay energizing circuits is completed through the switch and through a source of variable currents due to voice currents transmitted from one subscriber's line, one of the reinforcing circuits of the relay is simultaneously completed through the switch D and through means whereby the relay magnified currents are transmitted to the other subscriber's line, and similarly with respect to the other relay energizing circuit and the other reinforcing circuit. The sources of variable currents in the relay energizing circuits conveniently consist, as shown, of windings E¹ F¹ of transformers E F respectively, of which the other windings E² F² are in the lines leading to the corresponding subscriber's lines.

In the position of the parts shown in Fig. 1 it is assumed that the subscriber on line A is speaking; hence the transformer winding E¹ is the source of variable currents by which the relay C is energized, and the transformer winding F¹ is the means by which the magnified speaking currents from the terminals C² of the relay C are transmitted along the line L^b to the subscriber's line B. So long as the subscriber on line A continues to speak these conditions are maintained. When however, the subscriber on line A stops and the subscriber on line B commences to speak the arms D¹ D² of the double pole switch D are tilted in the opposite direction and the transformer winding F¹ then becomes the source of variable currents by which the relay C is energized while the transformer winding E¹ becomes the means by which the magnified speaking currents from the relay C are transmitted along the line L^a to the subscriber's line A.

The switch arms D¹ D² may be of the over-balancing pivoted type so that when once they have been thrown over electromagnetically by the energizing of the electromagnets d¹ d² they remain permanently in that position until thrown over electromagnetically in the reverse direction by the energizing of the electromagnets d₁¹, d₁².

The energizing of the two pairs of electromagnets is due to current derived from sources of steady current that become automatically switched across the respective line sections immediately the respective subscribers commence to speak. In connection with the subscriber's line A, the source of steady current shown for the line L^a consists of a battery A¹ connected on the one hand by way of a heavy inductance A² to the "line" wire and on the other hand by way of a front stop g and a tongue g¹ to the "return" wire. The tongue g¹ is normally kept against the front stop g by a spring g² or by gravity, but is moved away from the front stop and toward a back stop g³ when a controlling electromagnet A⁴ is energized by a steady current from a local battery A⁵. A condenser g⁴ prevents sparking at the stops g, g³. The circuit of the battery A⁵ is completed through a voice current responsive device A⁶. This device may conveniently take the form of a vibration device or "jumping switch" such as disclosed in the specification and drawings of my prior British Patent No. 9179 of 1912, that is to say a balanced or pivoted arm forming part of the circuit of the battery A⁵ and riding upon a resilient reed serving as armature to an electromagnet adapted to be energized by the voice currents. The actual surfaces at which the circuit of the battery A⁵ is thus rapidly interrupted are preferably composed of carbon. When

voice currents from the subscriber's line A are inductively transmitted to the electromagnet of the jumping switch A⁶, the armature of this switch vibrates and the balanced arm dances upon it, thereby destroying or reducing the steady current normally flowing in the electromagnet A⁴. The loss or reduction of the current in this electromagnet causes the tongue g¹ to move away from its back stop g³ and into contact with its front stop g thereby causing the battery A¹ to send along the line L^a a comparatively strong steady current to serve as the energizing current for the electromagnets d¹ d² by which the double pole change-over switch D is electromagnetically actuated to assume the position shown in Fig. 1. The right hand part of Fig. 1 corresponds to the left hand part, the jumping switch B⁶, heavy inductance B², and battery B¹ corresponding to the parts A⁵, A² and A¹ respectively; similarly the post office relay B⁴ corresponds to the electromagnet A⁴, with its tongue and stops.

The invention is not, of course confined to the means above described for enabling the voice currents in the subscriber's line A to be transferred to the transformer E and to effect the automatic throwing over of the arms of the throw-over switch. For example, the inductance A² might be connected at one end to the battery A¹ and at the other end to the mid point of an induction coil A^x connected across the line, the other pole of the battery being connected to earth, and an appropriate earth connection made at the other end of the line section, as shown in the fragmentary Fig. 1^a; obviously the inductance A² represented in this figure might be omitted.

Another modification is shown in Fig. 1^b, where it is seen that the electromagnet A⁴, of Fig. 1^a, and its tongue and stops are dispensed with, and that one contact of the jumping switch A⁶ is connected by way of an inductance A² to the mid point of an inductance A^x connected across the line, and the other contact connected to earth. A corresponding earth connection is made at the electromagnets d¹ d² (as in Fig. 1^a), and the battery for providing a steady current in the line is also inserted in this earth connection, an advantage being that the strength of the current at the contacts of the switch A⁶ is considerably attenuated and sparking is thereby minimized. In this arrangement (Fig. 1^b) it is to be noted that the four electromagnets controlling the switch arms D¹ D² are normally energized and that when either subscriber speaks the corresponding pair of electromagnets is temporarily deenergized, thus allowing the remaining pair to predominate and throw over the switch arms.

The jumping switches A⁶ B⁶ may be situ-

- ated at any point in the respective line sections, either close up to the relay apparatus or close up to the subscriber's line, but in order that they may respond promptly and readily to voice currents, they are preferably placed close to their respective subscriber's lines as shown in Figs. 1, 1^a and 1^b so as to be actuated by the voice currents before they suffer appreciable attenuation.
- 10 The electromagnet winding of each jumping switch may be connected across the "line" and "return" wires of the line proper as shown in Fig. 1^a; disturbances in the line, however, such for example as arise 15 from induction and from currents from the relay C are liable to actuate the switches, and I therefore prefer to protect each switch from such disturbances by constituting its electromagnet winding the bridge or 20 part of the bridge of a bridge connection as shown in Figs. 1, 1^b and 2, as will now be explained with reference to Fig. 1. Referring for convenience of description to the left hand end of the figure, it is seen that 25 the electromagnet winding terminals of the jumping switch A⁵ are connected, or "bridged" across the bridge arms A⁶ of a bridge connection. One end of each bridge arm is connected to the line proper L^a and 30 the other end is connected to part of the transformer winding by which the line L^a is inductively coupled to the subscriber's line A. A⁷ represents an artificial line which is more or less a copy of the subscriber's line with resistance and inductance at the end similar in values to those of the subscriber's telephone set. Consequently, when voice currents in the subscriber's line A are transferred by the transformer to the line proper L^a the jumping switch A⁵ is actuated and produces the results already described, but any currents passing backward along the line divide at the apex of the bridge connection and do 40 not affect the jumping switch, or only to a slight extent.
- 45 From the foregoing description of Figs. 1, 1^a and 1^b, the system represented by Fig. 2 will be readily understood without detailed description. It is to be noted that the bridge connection of the jumping switches A⁵, B⁵ is used, as in Figs. 1^a and 1^b, and that the circuits of the batteries A⁸ B⁸ are completed through the energizing coils of post office relays A⁴ B⁴, one terminal of the local circuit of each of these relays being connected to earth, and the other terminal connected to the mid-point of an induction coil (A^x B^x) as in Figs. 1^a and 1^b. The two pairs of electromagnets d¹ and d² and d¹, d², respectively operate in a similar manner to that described in connection with Fig. 1, but it is to be observed that a single source of steady current (battery X) serves for both lines L^a and L^b.

In the arrangements and methods of connection hitherto described, the operator at the relay station is unable to attend to any adjustment that may be required in the jumping switches A⁵ B⁵ and their accessories. If desired, however, the arrangement may be modified to render this possible, as shown for example in Fig. 3, where the jumping switches A⁵, B⁵, are shown close up against the transformers E and F respectively at the relay station. It will be understood that when voice currents traverse the line L^a, the jumping switch A⁵ destroys or reduces the steady current from the battery A¹ with the result that the electromagnetic devices controlled by the jumping switch B⁵ predominate and the double pole switch is thrown over into the position shown in the figure. Consequently the voice currents operate the relay C, and the reinforced currents are transferred by the transformer F to the line L^b. Corresponding effects take place if voice currents traverse the line L^b. It is however to be observed that the reinforced voice currents transferred through, say, the transformer F to the line L^b, cause the balanced arm of the jumping switch B⁵ to operate. Since the double pole switch arms D¹ D² have already been thrown over and are of the over-balancing type, the operation of the jumping switch B⁵ is of little importance provided this switch is not by chance active for an instant during which the switch A⁵ is quiescent. If the latter event took place the switch A⁵ would cause the switch arms D¹ D² to rock into their alternative position, the voice currents in the line L^a would then be unable to become reinforced by the relay. In order to avoid this occurrence several precautions may be adopted. According to one method the reinforced voice currents from the relay C are tapped by means of a transformer, as shown at H in Fig. 3, and the tapped portion of the current is made to traverse two coils A^{xx}, B^{xx}, which are associated with the jumping switches A⁵ B⁵ respectively in such a way as to cause their pivoted or balanced arms to dance and thereby insure that both switches are kept in an active condition so long as voice currents are passing through and being reinforced by the relay. This arrangement may in some cases present a defect in that, whereas the coils A^{xx} B^{xx} are traversed by the same current, the energizing winding of the jumping switch A⁵ is traversed by attenuated voice currents, when the energizing winding of the jumping switch B⁵ is traversed by the relay augmented voice currents, and similarly the switch B⁵ is traversed by attenuated currents when A⁵ is traversed by augmented voice currents, the result being that the two jumping switches are not subject to exactly the same condi-

tions. A preferable arrangement, therefore, is to so arrange the coils A^{xx} B^{xx} that they oppose the action of the respective energizing windings of the jumping switches. If, then, the electrical characteristics of the circuit of the coils A^{xx} B^{xx} are made equal to those of the lines L^a and L^b , as can be done by introducing an artificial line J of appropriate electrical value in the circuit of the coils A^{xx} B^{xx} , the currents in the coil B^{xx} will neutralize or oppose the currents in the energizing winding of the switch B^s when the reinforced voice currents are being transferred to the line L^b , whereas the similar currents in the coil A^{xx} will predominate over the attenuated currents in the energizing winding of the switch A^s , thus insuring that the switch B^s is kept quiescent and the switch A^s is kept active so long as voice currents are traversing the line L^a . Similarly when voice currents are traversing the line L^b , the switch B^s is kept active and the switch A^s is kept quiescent. In the arrangement just described, the coupling of the coil A^{xx} with the energizing winding of the switch A^s , and the coupling of the coil B^{xx} with the energizing winding of the coil B^s , must not be very close, since otherwise energy might be transferred back into the lines L^a or L^b . Instead of having to avoid the too close coupling above referred to, a modified system may be adopted as shown in Fig. 4. In this arrangement, the relay augmented current tapped by way of the transformer H is made to operate a jumping switch C^s which controls the circuit of a battery c^s by means of which the energizing coils d^1 d^2 , d_1^1 d_1^2 , are supplied with current by way of the jumping switches A^s B^s . So long as the relay is operating to reinforce voice currents arriving from either direction, say from the line L^a , as represented by the drawing, the jumping switch C^s is active and the steady current that might otherwise flow from the battery c^s in the coils d^1 d^2 , d_1^1 d_1^2 is destroyed or reduced, so that in the event of a momentary quiescence of the jumping switch B^s the arms of the double pole switch are not thrown over.

What I claim and desire to secure by Letters Patent of the United States is:—

1. In a telephone relay system between two terminal stations, the combination with relay apparatus, relay energizing circuits through which voice currents from the terminal stations may pass, and relay circuits through which the relay magnified currents may pass, of switching means normally assuming and maintaining either of two positions in one of which the relay energizing circuit corresponding to one station is closed and receiving conditions for the distant station are established, while in the other position the relay energizing circuit for the last mentioned station is closed and receiving

conditions for the first mentioned station are established, and means whereby the voice currents from either terminal station automatically cause the switching means to assume the position in which the distant station can receive the relay magnified currents, if said means are not already in that position. 79

2. In a telephone relay system between two terminal stations, the combination with relay apparatus, relay energizing circuits through which voice currents from the terminal stations may pass, and relay circuits through which the relay magnified currents may pass, of a double-pole overbalancing change-over switch normally assuming and maintaining either of two positions in one of which, the relay energizing circuit corresponding to one station is closed and receiving conditions for the distant station are established, while in the other position the relay energizing circuit for the last mentioned station is closed and receiving conditions for the first mentioned station are established, and means whereby the voice currents from either terminal station automatically cause the change-over switch to assume the position in which the distant station can receive the relay magnified currents, if said switch is not already in that position. 80 85 90 95

3. In a telephone relay system between two terminal stations, the combination with relay apparatus, relay energizing circuits through which voice currents from the terminal stations may pass, and relay circuits through which the relay magnified currents may pass, of a double-pole overbalancing change-over switch normally assuming and maintaining either of two positions in one of which, the relay energizing circuit corresponding to one station is closed and receiving conditions for the distant station are established, while in the other position it closes the relay energizing circuit for the last mentioned station is closed and receiving conditions for the first-mentioned station are established, electromagnetic devices for moving the double-pole change-over switch into either position, and means whereby voice currents from either one station cause the activity of the respective electromagnetic device that moves the change-over switch into the operative position for bringing about magnification and transmission of the voice currents to the other station. 100 105 110 115

4. In a telephone relay system between two terminal stations, the combination with relay apparatus, relay energizing circuits through which voice currents from the terminal stations may pass, and relay circuits through which the relay magnified currents may pass, of a double-pole overbalancing change-over switch normally assuming and maintaining either of two positions in one of which, the relay energizing circuit corre- 120 125 130 135

sponding to one station is closed and receiving conditions for the distant station are established, while in the other position it closes the relay energizing circuit for the 5 last mentioned station is closed and receiving conditions for the first mentioned station are established, electromagnetic devices for moving the double-pole change-over switch into either position, electromagnetic 10 means for controlling the energizing circuits of the said electromagnetic devices, and electromagnetic devices responsive to voice currents whereby on speaking at either station the corresponding electromagnetic means 15 complete the energizing circuit of the corresponding electromagnetic device and thereby correspondingly actuate the change-over switch.

5. In a telephone relay system between 20 two terminal stations, the combination with relay apparatus, relay energizing circuits through which voice currents from the terminal stations may pass, and relay circuits through which the relay magnified currents 25 may pass, of a double-pole overbalancing change-over switch, which in one position closes the relay energizing circuit corresponding to one station and establishes receiving conditions for the distant stations, 30 while in the other position it closes the relay energizing circuit for the last mentioned station and establishes receiving conditions for the first mentioned station, electromagnetic devices for moving the double-pole 35 change-over switch into either position, electromagnetic means for controlling the energizing circuits of the said electromagnetic devices, a "bridge" connection in the line wire between each station and the relay apparatus, and an electromagnetic device responsive to voice currents included in the "bridge" of each bridge connection for operating said electromagnetic means, substantially as and for the purpose specified.

45 6. In a telephone relay system between two terminal stations, the combination with a single relay common to both stations, of a double-pole change-over switch which in one position closes the relay energizing circuit 50 corresponding to one station and establishes receiving conditions for the distant station, while in the other position it closes the relay energizing circuit for the last mentioned station and establishes receiving conditions for 55 the first mentioned station, and transformers whereby voice currents from the line proper of each station are transferred to the corresponding relay energizing circuit or the relay magnified voice currents are transferred 60 to the line proper according to the direction of speech transmission, switch actuating electromagnets electrically connected in the line proper, means for sending a steady cur-

rent through the line to energize the electromagnets, electromagnetic devices for rendering the aforesaid means operative, and devices responsive to voice currents whereby on speaking at either station the corresponding switch actuating electromagnets become active.

7. In a telephone relay system between two terminal stations, the combination with relay apparatus, relay energizing circuits through which voice currents from the terminal stations may pass, and relay circuits 75 through which the relay magnified currents may pass, of a change-over switch which in one position closes the relay energizing circuit corresponding to one station and establishes receiving conditions for the distant 80 station, while in the other position it closes the relay energizing circuit for the last mentioned station and establishes receiving conditions for the first mentioned station, electromagnets electrically connected in the line 85 proper from each terminal station, means whereby the electromagnets become energized, electromagnetic devices responsive to voice currents whereby on speaking at either station the circuit-closing means of the electromagnets become operative in closing their energizing circuits and thereby bring about actuation of the change-over switch, and means whereby the effect of the relay-augmented voice currents on the voice-current-responsive device that is associated with the section of the line to which such currents are being transmitted is neutralized or counteracted for so long as the relay apparatus continues to operate for the direction in question.

8. In a telephone relay system between two terminal stations, the combination with a single relay common to both stations, of a double-pole change-over switch which in one position closes the relay energizing circuit 10 corresponding to one station and establishes receiving conditions for the distant station, while in the other position it closes the relay energizing circuit for the last mentioned station and establishes receiving conditions for 110 the first mentioned station, electromagnets associated with the switch and electrically connected to the line proper from each terminal station, a battery connected to send a divided steady current along the line to energize the electromagnets, battery circuit closing means, and electromagnetic devices responsive to voice currents whereby on speaking at either station the battery circuit closing means close the battery circuit.

In testimony whereof I affix my signature in presence of two witnesses.

SIDNEY GEORGE BROWN.
